UNITED STATES PATENT OFFICE.

ROSCOE S. SHELDON, OF WEST ALLIS, WISCONSIN.

COMBINED FORCE-PUMP AND SPRAY-TANK.

No. 921,010.

Specification of Letters Patent. Patented May 11, 1909.

Application filed October 12, 1906. Serial No. 338,561.

To all whom it may concern:

Be it known that I, ROSCOE S. SHELDON, a citizen of the United States, residing at West Allis, county of Milwaukee, and State of Wisconsin, have invented new and useful Improvements in a Combined Force-Pump and Spray-Tank, of which the following is a specification.

My invention relates to improvements in a combined pump, pneumatic pressure tank and sprinkler, and it pertains to that class of devices in which the required pneumatic pressure for sprinkling purposes or for raising water to a higher elevation is obtained by forcing water into an air-tight tank against the air contained therein, whereby when a given quantity of water has been forced into the tank the water will be forced therefrom by the elasticity of the air confined therein above the water, my device being so constructed that when the pressure has been reduced by drawing off the water and it is not convenient to renew the pressure by again replacing the supply of water as it is frequently the case when using the device for sprinkling vegetables the pressure may be renewed by employing the same power for pumping air into the tank, the pump being adapted to be used for pumping both air and water.

The construction of my invention is explained by reference to the accompanying drawing which represents a longitudinal vertical section thereof.

The several parts are referred to by index characters.

1 represents an air tight tank and 2 the cylinder of a pump.

13 is a piston which is provided with a central aperture 4. The aperture 4 is closed by the valve 5 which valve is hinged at one side to one side of the aperture formed in the piston.

6 is a bracket by which motion is communicated from the piston rod 7 to the piston.

8 is an operating handle which is adapted to be manually operated by the user.

The rod 7 is connected with the cylinder 2 of the pump through an ordinary stuffing nut 9 and packing 10.

For convenience of construction I preferably employ an ordinary clapper valve which may be formed of leather integrally with the piston.

3 is a spring by which the valve 5 is normally retained in its closed position. When,

however, the piston is drawn upward against the contents above it, said valve will be thrown downward and opened, when with the return or downward stroke, said valve 5 will be closed by the action of the spring 3 coöperating with the liquid below it.

The cylinder 2 is provided at its lower end with a cylinder head 14 through which an outlet aperture 15 is formed. The aperture 15 is closed with the valve 16, said valve being hinged at one side to the cylinder head 14.

17 is a spring by which the valve 16 is closed with the upward movement of the piston. When, however, the piston is moved downward, said valve will open and the contents of the cylinder will be discharged into the tank 1.

18 is the upper cylinder head of the pump 75 which is provided with an internal screw threaded bearing 19 for the reception of the annular collar 20. The annular collar 20 is provided with an external screw thread 21. The collar 20 is first soldered or otherwise secured to the exterior surface of the pump cylinder 2.

The cylinder head 18 is then screwed down about mid-way upon the collar 20. This being done the set screw 22 is turned inwardly so as to impinge against the 85 collar and prevent the head 18 from turning thereon. When the head, collar and pump cylinder have been thus secured together, the pump cylinder is placed within the tank 1 when the lower portion of the collar 20 is 90 screwed into the inclosing collar 23. The collar 23 is soldered or otherwise rigidly secured to the tank 1.

It will be obvious that when desirous to remove the piston and cylinder from the tank 1 together this object is 95 readily accomplished by turning the cylinder head 18, when the collar 20 will be unscrewed from the collar 23, and the cylinder 2 together with the piston therein can be readily removed from the tank. If, however, it 100

should be desired to remove the piston from the pump cylinder without removing the cylinder from the tank the set screw 24 is turned in slightly so as to impinge the periphery of the collar 20 and prevent the collar from unscrewing and the set screw 22 is turned back in its bearings so as to become disengaged from the collar 20 when the cylinder head 18

can be readily unscrewed from said collar 20 and the piston withdrawn from the cylinder 105 without the cylinder being removed from the tank.

110

25 is an inlet duct through which the water, air or other fluid is drawn from the exterior into the pump.

26 is an outlet duct through which the contents of the tank are discharged.

27 is a spray nozzle by which the contents of the tank may if desired be discharged in a spray.

The duct 26 communicates with the lower 10 end of the tank 1 through the pipe 28, whereby when the required air pressure is applied within the tank, the greater portion of the liquid contents will be forced out through said duct. It will be understood that the 15 liquid in the tank will be forced by the compressed air above out through the pipe 28. 29 is a fluid controlling valve by which the escape of the liquid under pneumatic pressure is controlled.

20 While my device is especially adapted to be used for spraying paris green,—liquids, and other substances upon growing vegetation for the purpose of destroying insects, it is obvious that if desired the duct 25 may be 25 connected with an ordinary cistern or water reservoir and the duct 26 with the water pipes of an ordinary dwelling in which case a person may by operating the pump store up a supply of water in the tank 1 under pressure which will be discharged to any of the 30 faucets connected therewith as soon as they are opened. When my device is thus used the size of the tank may be increased proportionately according to the quantity of water 35 it is desirous to store.

30 is a strap by which the tank may be suspended from a person's shoulder when using the same for spraying vegetation. The strap 30 is suspended at the respective 40 ends of the tank with links and fastening plates in the ordinary manner.

It will be obvious that when the required air has been supplied and the valve 29 opened the contents of the tank will be discharged 45 therefrom under pneumatic pressure through the ducts 26 and nozzle 27. It will of course be understood that when the liquid is thus discharged from the tank, the pressure will gradually diminish. Assuming that the 50 pressure has been thus diminished when the user is at a distance from the liquid supply he can readily restore the pressure by a few strokes of the piston by means of which an additional supply of air will be forced into 55 the tank.

It is a well known fact that in operating a

pump, the necessary power is much more easily applied with a down stroke than with an upstroke of the piston. By the arrangement of the coöperating parts shown and described, the liquid from the exterior is drawn into the cylinder of the pump above the piston, while the liquid below the piston is simultaneously forced therefrom into the enclosing tank, whereby the entire work of both 60 drawing the liquid into the cylinder and forcing it therefrom is performed by the down stroke of the piston, it being understood that the liquid above the piston simply passes through the check valve in the piston 65 to the space in the pump cylinder below as the piston is raised, whereby the operator has simply to overcome the friction of the moving parts with the upstroke of the piston.

Having thus described my invention what 75 I claim as new and desire to secure by Letters Patent is—

In a device of the described class the combination of an air tight tank, a pump cylinder centrally suspended at its upper end from 80 the upper end of said tank, a cylinder head adapted to close the upper end of said pump cylinder and provided with a central aperture, a piston rod located in said central aperture, an air tight packing located 85 around said piston rod, a piston connected with the lower end of said piston rod and provided with a central aperture, a valve adapted to close the central aperture of said piston with a downward stroke, a cylinder 90 head connected with the lower end of said cylinder and provided with a central aperture, a valve adapted to close the aperture in said last named cylinder head with the upstroke of the piston, means for automatically closing both of said valves, and an inlet liquid duct connected with said cylinder head above the piston, means for securing 95 said cylinder head to said cylinder and means for securing said cylinder to said air tight 100 tank, the arrangement of the coöperating parts being such that the pump cylinder above the piston is filled while the liquid below the piston is simultaneously forced from the cylinder by the down stroke of the piston. 105

In testimony whereof I affix my signature in the presence of two witnesses.
